UNITED STATES PATENT OFFICE.

DAVID G. LORRAINE, OF LOS ANGELES, CALIFORNIA, ASSIGNOR OF ONE-HALF TO
WILLARD L. BURROUGH, OF FULLERTON, CALIFORNIA.

THROTTLING DEVICE.

Application filed June 1, 1922. Serial No. 565,147.

To all whom it may concern:

Be it known that I, DAVID G. LORRAINE, a citizen of the United States, and resident of Los Angeles, county of Los Angeles, State of California, have invented new and useful Improvements in Throttling Devices, of which the following is a specification.

This invention relates to throttling devices particularly adapted to be employed in pipe lines from oil wells.

It is the object of the invention to provide a device of this character whereby the flow may be readily regulated by adjusting the opening in the device through which the oil passes.

It is a further object of the invention to provide a regulating means of this character, comprising a seat and a head adjustable relative thereto, mounted in a casing, and arranged whereby said seat and head may be removed and replaced without disconnecting the pipe line from said casing.

It is a still further object of the invention to provide indicating means associated with the adjustable head, so that the size of the opening for the passage of the flow may be conveniently ascertained, and set as is found desirable.

The invention further provides means for guiding the movement of the adjustable head so as to properly align the same with its cooperating seat, the head being preferably an elongated conical member, and the cooperating seat, an elongated bushing having a tapering bore.

Further objects of the invention will be readily understood from the following description of the accompanying drawings, in which:

Fig. 1 is a side elevation partly in axial section.

Figs. 2, 3, and 4 are detail sections on the lines 2-2, 3-3, and 4-4 of Fig. 1.

The casing of the device is shown at 1, as a usual T construction having the flanged inlet 2, and the flanged outlet 3, angularly disposed with relation to the inlet. A flanged opening 4 is at the rear of the casing in alignment with outlet 3.

The seat of the device is an elongated bushing 5 having a tapering bore 6, said seat being detachably mounted in the casing at the outlet, and arranged for removal and replacement through opening 4.

As an instance of this arrangement, a disc

7 is adapted to be received against the flange of outlet 3 and supported over said outlet, said disc having a threaded bore 8 in alignment with the outlet. The end of bushing 5 has a shoulder 9 adapted to abut against disc 7, with the threaded end of said bushing removably received in threaded bore 8, for mounting the bushing in position.

Pipe section 10 adapted to extend from outlet 3, has a detachable flange 11, and in assembling the parts, disc 7 is fixed against the flanged outlet, by flange or annulus 11 received against the same, usual bolts 12 extending through the flange of the outlet, disc 7, and flange 11, to form retaining means.

Pipe section 13 may be connected to inlet 2, by a usual flange 14 on said pipe section received against the flange of the inlet, with bolts 15 received through the flanges to form retaining means.

A guide adapted to receive the adjustable head cooperating with bushing 5 extends into the casing and is preferably mounted at opening 4. The guide is shown as a tubular member 16, having a flange 17 adjacent its outer end and adapted to be received against the flange of opening 4, for positioning the guide in the casing in spaced relation from, and in axial alignment with bushing 5.

A yoke 18 extends rearwardly from opening 4, and has a flanged end 19 received against flange 17, with bolts 20 extending through flanges 19 and 17, and the flange of opening 4, for retaining the guide and the yoke in position.

The yoke has a threaded bore 21 in alignment with opening 4, and a screw rod 22 is threaded through the same, with operating means shown as a hand wheel 23 upon the outer end of said screw rod.

The screw rod extends into the tubular guide, preferably with a packing gland 24 between the rod and guide, and the inner end of the rod is received in a recess 25 provided in the end 28 of an elongated conical head 27 which is mounted in the guide.

The recessed end of the head is preferably cylindrical so as to fit snugly in the guide tube, and a pin 26 is removably received through said end of the head and the end of screw rod 22, so that the tapering head may be readily replaced.

The conical head tapers toward bushing 5, and is so constructed, that actuation of the screw rod will longitudinally adjust the head in the tapered bore of the bushing, for adjusting the size of the opening through said bushing.

Indicating means are provided for showing the position to which head 27 is adjusted with relation to bushing 5. As an instance 10 of this arrangement, a graduated bar 30 is mounted on one arm of yoke 18, and a co-operating pointer 31 arranged on screw rod 22.

The mounting of the pointer preferably 15 includes a shoulder 32 on the screw rod, with a bearing head 33 on the pointer received on the rod against said shoulder. A collar 34 is fixed on the screw rod so as to hold the bearing head against shoulder 32 20 while permitting turning of the screw rod relative to the pointer. The pointer will thus be shifted axially with the screw rod and the head 27, and by a guide strip 30^a which overlies the pointer the latter is held 25 against turning with the screw rod and is maintained in position cooperating with the graduated scale.

It will be noted that the construction as 30 described provides for adjustment of the passage for the flow through bushing 5, by axial movement of the tapering head in the tapered bore of the bushing, and that means are provided for indicating the adjusted position of the head and the resulting 35 regulation of the flow opening.

It will further be observed that the invention provides for removal and replace-

ment of the wearing parts, through the opening 4 at the rear of the casing, without necessitating the disconnection of the sections of the pipe line from casing 1. 40

While I have illustrated and described, what I now believe to be the preferred practical embodiment of the device, it will be apparent that various changes may be made 45 in the construction, combination, and arrangement of parts, without departing from the spirit of the invention.

What is claimed is:

1. In a device of the character described, 50 a casing having an opening and a valve seat surrounding said opening, a head cooperating with said seat adapted to close said opening, a threaded operating member adapted for longitudinal adjustment of said head 55 relative to said seat, a graduated scale, said operating member having a shoulder thereon, a pointer cooperating with said scale and having a bearing received on said operating member against said shoulder, and a 60 collar fixed on said operating member against said bearing.

2. In a device of the character described, 65 a casing having an outlet, a member having a bore provided with attaching means, an annulus received against said member and fixed to said casing for positioning said member against said casing and over said outlet, and a bushing in said casing detachably engaged by said attaching means. 70

In testimony whereof I have signed my name to this specification.

DAVID G. LORRAINE.
